HIGH FREQUENCY MODULATING AND TRANSMITTING SYSTEM

George T. Royden, South Orange, N. J., assignor to Federal Telegraph Company, Newark, N. J., a corporation of New Jersey

Application January 7, 1938, Serial No. 183,773

6 Claims. (Cl. 179—171)

1. The present invention relates to high frequency transmitting systems wherein a high frequency carrier is modulated in accordance with high frequency signals and then transmitted to an antenna or transmission line. More particularly the invention relates to a system for providing a carrier of sufficient amplitude for transmission to a remote point modulated faithfully in accordance with a high frequency signal.

2. The invention is particularly applicable to television transmission systems. In such systems it is usual to generate the high frequency carrier and amplify this carrier in a chain of successive amplification stages before transmitting it to the transmission line or radiating antenna for delivery to a remote point. In some cases the carrier is generated in the scanning arrangement of the television system itself so that the modulation may be said to take place in the scanning device. In other cases a separate modulating arrangement is employed. In either type of system, however, it is generally the practice to modulate the carrier at a very early stage in the chain of amplification. Such systems with modulation at an early stage require that all amplifiers subsequent to the modulation stage shall have very linear characteristics, and for the wide band of frequencies required for television such linearity is difficult to attain.

3. It is therefore an object of the present invention to provide a television transmitting system of the type wherein a carrier is generated and amplified in a chain of successive amplification stages before delivery to a transmission line or antenna for transmission to a remote point, but in which modulation of this carrier is effected in the last stage, or one of the later stages of the amplification chain.

4. It is also another object of the present invention to provide a novel modulation circuit particularly adapted for performing the modulation in the above mentioned television transmitting system. More generally it is an object to provide a modulation system which will efficiently and faithfully modulate a high-power, high-frequency carrier in accordance with a modulating signal which is itself of high frequency.

5. It is a particular object of the present invention to provide a modulating system having a modulating tube and a driver tube arranged in series, which is suitable for modulating a high-power, high-frequency carrier in accordance with a high-frequency signal in a faithful and linear fashion so that the envelope of the modu-

lated carrier constitutes a high fidelity representation of the waves formed of the high-frequency modulating signals. More especially it is an object of the present invention to provide such a modulation system in which distortions due to overloading of the modulating tube by stray capacity effects are eliminated by a shield maintained at a varying potential.

6. The invention can best be understood by reference to the attached sheet of drawings, in which

Fig. 1 represents a modulating and transmitting system for television in accordance with the present invention;

Fig. 2 represents those parts of the series modulation arrangement of Fig. 1 which are essential for understanding the principles of the varying-potential shield of my invention;

Figs. 3 and 4 are schematic equivalent networks used for analysis of the circuits of Figs. 1 and 2 at the frequency of the modulating signals.

7. Referring more particularly to Fig. 1, a carrier frequency oscillation generator 1 is connected to supply a carrier frequency to a radiating antenna 2 by way of a chain of amplifiers 3, a modulating tube 4 and a transmission line 5. A tuned coupling unit 6 comprising a primary 7, a secondary 8 and a tuning condenser 9 serves to couple the grid circuit of the modulating tube 4 to the chain of amplifiers 3. Another tuned coupling unit 10 couples the output of the modulating tube 4 to the transmission line 5; a third coupling unit 11 serves to couple the transmission line 5 to the antenna 2. A television scanner 12 supplies modulating signals through signal amplifier 13 to a pair of driver tubes 14 and 15. Driver tube 14 serves to apply the amplified modulating signals to the modulating tube 4, these two tubes 4 and 14 being actually connected in series with each other with respect to plate current source 16, so that variations in the resistance of driving tube 14 cause corresponding variations in the effective plate potential of modulating tube 4. The other driver tube 15 is provided for a purpose more fully explained hereafter.

8. Thus the modulating signals developed in device 12 and amplified in device 13 serve to vary the internal resistance of driver tube 14 which in turn varies the effective plate voltage of modulating tube 4. As a result of this variation in its effective plate voltage, modulating tube 4 controls the amplitude of the carrier transmitted from amplifier chain 3 in a faithful, substantially linear manner so that the envelope of the carrier delivered through coupling unit 10 to the

transmission line 5 corresponds accurately to the variations of the effective plate voltage of the modulating tube 4.

The cathode of the modulating tube 4 which is preferably of filamentary type as shown, is energized from a suitable source of alternating power through a filament transformer which comprises a primary 17 and a secondary 18 adapted to be shielded from one another electrostatically as more fully explained hereafter. A grid leak 19 together with a pair of by-pass condensers 20 and 21 are connected in the grid return circuit of the modulating tube 4 as shown, to serve as biasing means for the grid of this modulating tube. This leak and pair of condensers 19, 20 and 21 act in similar manner to the well known grid leak and condenser ordinarily employed, but the connection shown as somewhat superior to the usual connection from the standpoint of balance. If the distributed capacity of primary 17 is not sufficient to by-pass the plate of driver tube 14 to the filament of modulating tube 4, further condensers may be connected across the two halves of this primary.

The filamentary cathodes of driver tubes 14 and 15 are similarly energized from the same alternating current source by means of transformers, but since these transformer connections do not form an essential part of the present invention they need not be described in detail but can be sufficiently understood from the drawing.

A shield 22 is disposed so as to enclose not only the modulating tube 4 and the driver tube 14, but also the primary 17 of filament transformer 16 and the leak and condenser combination 19, 20, 21, as well as the secondary 8 and condenser 9 of the tuned coupling unit 6 previously described. This shield 22 is disposed so as to electrostatically shield all the elements enclosed within it from external portions of the circuit and from ground. By "ground" is meant either the actual earth or the surrounding environment. Thus if the equipment is housed in a cabinet the potential of this cabinet is to be considered as ground potential, while if the equipment is mounted on a chassis but not housed the average potential of the chassis and other surroundings is to be taken as ground potential. It is desirable also to reduce the capacity between shield 22 and ground as far as is conveniently possible and for this purpose all the elements shown in Fig. 1 as being within the shield are preferably grouped together as closely as possible and arranged so that the shield can readily enclose them all without being of excessive size.

The shield 22 is connected to the second driver tube 15 so that the potential of this shield will be controlled by this second driver tube. Preferably the shield is directly connected to the anode of the driver tube 15 as shown, and a load impedance 23 is interposed between the plate of this tube and the power source 16 so as to regulate the phase and amplitude of the potential variation of the shield 22. The second driver tube 15 is fed in parallel with the first driver tube 14 from the amplifier 3, as shown in Fig. 1, and the load impedance 23 is so proportioned with respect to the effective impedance of shield 22, that the potential of shield 22 will vary in substantially the same manner as the potential of the plate of driver tube 14. The function of this shield 22 whose potential varies as above described, is to reduce the effective variation of potential of all those elements connected to the anode of driver tube 14 with respect to their sur-

roundings, so that the charging current drawn by all these elements will be reduced so as not to overload the driver tube 14. The significance of this arrangement can best be understood from a consideration of Figs. 2, 3 and 4.

Fig. 2 schematically represents sufficient of the series modulating connections of tubes 14 and 4 to enable the function of the shield 22 of Fig. 1, to be clearly understood. As is clearly evident in Fig. 2, all the elements 8, 9, 17, 19, 20, 21 as well as the filament and grid of modulating tube 4 and the anode of driver tube 14 and all the wiring interconnecting the above named parts, may conveniently be considered as one element with respect to the frequency of the modulating signals 11 since for this signal frequency the impedance of the tuned circuits 7 and 8 will presumably be negligible. All these parts and their interconnecting wiring, therefore, may most conveniently be considered as one element having at any one instant one potential so far as the signal frequency waves are concerned, and for convenience all these parts and their wiring have been shown dotted in Fig. 2 and are collectively designated as Y. The capacitance of all these elements with respect to ground may be collectively designated as C_y and may be approximately represented by a comparatively large condenser as shown in Fig. 3.

The anode X of modulating tube 4 may also 30 be considered to be directly connected to ground since the impedance of coupling device 10 may be assumed to be negligible at the frequency of the modulating signal, and since the plate current source 16 may be assumed to have negligible impedance at this frequency if it is properly bypassed. The collective capacities of all the parts generally designated Y with respect to the anode X of modulating tube 4 may be collectively designated C_{xy} and may be approximately represented 35 by a condenser as in Fig. 3. The cathode of driver tube 14 may also be considered as directly connected to ground and as having a capacity with respect to all the parts Y. The grid of this modulating tube 14 cannot accurately be considered as connected to the cathode of the tube 14 because a very considerable impedance exists between these two electrodes. Nevertheless, by taking account of the variations of potential of the grid of tube 14 the grid and cathode of the 50 tube 14 may be grouped together as Z, and for any given potential variations of Y and of the grid the capacity between Y and Z may be approximately represented by a condenser C_{yz} as in Figs. 3 and 4. The internal resistances of tubes 14 and 4 may 55 be approximately represented as resistors R_{14} and R_4 as shown in Fig. 3.

Referring to the schematic diagram of Fig. 3, which approximately represents the impedance relations of the circuit of Fig. 2 for the signal frequency waves, the signal frequency energy developed in tube 14 is represented as developed by a generator V_{14} in series with a resistor R_{14} . As can be seen perhaps most clearly in Fig. 3, in order to develop a given modulating potential 65 across R_{14} a large current must be supplied by generator V_{14} through resistor R_{14} because of the large capacity C_y . This represents a considerable load on the driver tube 14 and thus leads to distortion.

In accordance with the present invention, however, the large charging current of condenser C_y is prevented by means of the shield 22 shown in Fig. 1 and Fig. 4, which effectively splits the condenser C_y shown in Fig. 3 into two condensers C_{yz} 75

and C_s connected in series as shown in Fig. 4. The condenser C_{ys} represents the capacity between all of the parts Y and the shield 22 while the other condenser C_s represents the capacity of the shield 22 to ground. To the intermediate point between these two condensers is then connected the signal frequency energy developed in auxiliary tube 15. This energy is represented in Fig. 4 as developed by generator V_{15} in series with resistor R_{15} and shunted by load impedance 23 of suitable value. As far as possible the load impedance 23 is adjusted so as to cause shield 22 to vary in potential in nearly the same manner as all of the parts collectively designated as Y . By this expedient the charging current required for charging the parts Y is greatly reduced so that the driver tube 14 is enabled to operate substantially without distortion.

20 By this arrangement the efficiency and high-power linear modulation qualities of the series modulation circuit are attained and at the same time the overloading of the driver tube 14 is obviated. Thus the total modulation system is 25 enabled to operate at a high efficiency and with practically no distortion, and is capable of modulating a carrier of sufficiently high power so that this carrier may be directly employed for transmission to a remote point without further 30 amplification or with only a small amount of further amplification.

Although it is preferred to enclose all of the parts collectively designated as Y within the floating shield 22, it is possible to attain many of the 35 advantages of the present invention by enclosing only certain ones of these parts within the shield. It is possible, for example, to arrange the shield so that the driver tube 14 is wholly or 40 partially outside of this shield, although in such a case there will be an appreciable capacity between the anode of the driver tube and ground, which capacity will not be compensated by the 45 shield. Also it should be understood that the floating shield need not be fed by an auxiliary tube connected in parallel with the driver tube 14, but may be otherwise energized provided that the potential of this shield is varied approximately in accordance with the potential of the 50 parts collectively designated as Y , so as to reduce the charging current, ground, to driver tube 14.

In the preferred embodiment above described and illustrated, the series connection of the driver and modulator tubes is effected by connecting the modulator tube on the positive side of the driver tube with the cathode of the latter tube grounded. Some of the advantages of the invention may be attained, however, with the relative positions of these two tubes inter- 55 changed and/or with some other point in the circuit grounded. Also the output circuit 10 may be disposed in a different position although the disclosed arrangement is preferred.

Although I have shown and disclosed certain 60 embodiments of my invention for the purpose of illustration, it will be understood that modifications, adaptations and variations thereof occurring to one skilled in the art may be made without departing from the scope of my invention as 65 defined in the appended claims.

70 What I claim is:

1. A television modulation system for modulating a high frequency, high power carrier in accordance with high frequency signals which 75 comprises a modulator space discharge device

having a modulating space discharge path, a driver space discharge device having a driving space discharge path, a current source, means for connecting the space discharge paths in series with each other and said source, means for applying said carrier to said modulating path, means for varying the impedance of said driving path in accordance with said signals for effecting modulation of said carrier, shielding means for dividing the effective capacity across said 10 driver discharge path into two serially related capacities, and means for varying the potential across one of said two capacities substantially in accordance with variations of potential across said driver discharge path at least with respect 15 to said signals.

2. A television modulation system for modulating a high frequency, high power carrier in accordance with high frequency signal which 20 comprises a modulator space discharge device 25 having a modulator anode and a modulator cathode and a modulating space discharge path therebetween, a driver space discharge device having a driver anode and a driver cathode and a driving space discharge path therebetween, a current source, means for connecting said driver anode to said modulator cathode and said driver cathode and modulator anode to said source, connections between said current source and ground, means for applying said carrier to 30 said modulating path, means for varying the impedance of said driving path in accordance with said signals for effecting modulation of said carrier, shielding means for dividing the effective 35 capacity between said modulator cathode and ground into a first capacity between said modulator cathode and said shield and a second capacity between said shield and ground, and means for varying the potential of said shield substantially in accordance with potential variations 40 of said modulator cathode at least with respect to said signals.

3. A television modulation system for modulating a high frequency, high power carrier in accordance with high frequency signals which 45 comprises a modulator space discharge device having a modulator anode and a modulator cathode and a modulating space discharge path therebetween, a driver space discharge device having a driver anode and a driver cathode and 50 a driving space discharge path therebetween, a current source, means for connecting said driver anode to said modulator cathode and said driver cathode and modulator anode to said source, connections between said current source and 55 ground, other apparatus having a considerable distributed capacity to ground, connections between said modulator cathode and said other apparatus, means for applying said carrier to said modulating path, means for varying the impedance of said driving path responsive to said signals so as to vary the potential of said driver anode and modulator cathode in accordance with said signals for effecting modulation of said carrier, a shield around said other apparatus, and 60 means for varying the potential of said shield substantially in accordance with the potential of said driver anode thereby reducing the effective capacity between said other apparatus and ground with respect to said signals. 70

4. A television modulation system for modulating a high frequency, high power carrier in accordance with high frequency signals which comprises a modulator space discharge device having a modulator anode and a modulator cath- 75

ode and a modulating space discharge path therebetween, a driver space discharge device having a driver anode and a driver cathode and a driving space discharge path therebetween, a current source, means for connecting said driver anode to said modulator cathode and said driver cathode and modulator anode to said source, connections between said current source and ground, other apparatus having a considerable distributed capacity to ground, connections between said modulator cathode and said other apparatus, means for applying said carrier to said modulating path, means for varying the impedance of said driving path responsive to said signals so as to vary the potential of said driver anode and modulator cathode in accordance with said signals for effecting modulation of said carrier, a shield around said other apparatus, a further space discharge device having a further anode and a further cathode and a further space discharge path therebetween, means for varying the impedance of said further path in accordance with said signals, and means for varying the potential of said shield responsive to the impedance variations of said further path in substantially the same phase and amplitude as the

potential of said driver anode thereby reducing the effective capacity between said other apparatus and ground with respect to said signals.

5. A carrier signalling system comprising a first discharge tube and a second discharge tube serially connected, the cathode of said first tube being connected to the anode of said second tube, means associated therewith and forming undesired capacity between the point of interconnection of said tubes and the cathode of said second tube, a shield around said means, means for applying a carrier frequency to said first tube, and means for simultaneously varying the impedance of said second tube and the potential of said shield to reduce said undesired capacity effect.

6. A system according to claim 5, wherein said means for simultaneously varying the impedance of said second tube and the potential of said shield comprises a third discharge tube having its anode connected to said shield and its cathode connected to the cathode of said second tube, and common means for varying the impedances of said second and third tubes in the same phase relation.

GEORGE T. ROYDEN.
